DESCRIPTION

U.S. PATENT DOCUMENTS

FIG. 1 is a front, right and top perspective view of a smart
entrance guard with portable tracker;

FIG. 2 is a front, left and top perspective view of the smart
entrance guard with portable tracker;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is shows that a portable tracker is detachably com-
bined with the smart entrance guard with portable tracker by
a magnet.
